UNITED STATES PATENT OFFICE.

BENJAMIN E. MORSE, OF CANTON, MASSACHUSETTS.

SHEET-METAL CAN-OPENER.

No. 918,074.

Specification of Letters Patent. Patented April 13, 1909.

Application filed November 20, 1908. Serial No. 463,521.

To all whom it may concern:

Be it known that I, BENJAMIN E. MORSE, a citizen of the United States, and resident of Canton, in the county of Norfolk and State of Massachusetts, have made certain new and useful Inventions Relating to Sheet-Metal Can-Openers, of which the following is a specification, taken in connection with the accompanying drawing, forming part of the same.

This invention relates to sheet metal can openers and relates especially to can openers formed of sheet metal and pivotally attached by a pivot formed integral with the opener to the cover flange of the can so as to bring a suitable grip into forcible engagement with the can lip when the opener is operated.

In the accompanying drawings showing in a somewhat diagrammatic way illustrative embodiments of the invention and in which the same reference numerals refer to similar parts in the several figures, Figure 1 is a side elevation of one form of opener mounted upon the can parts being broken away to indicate the operation. Fig. 2 is an enlarged side sectional view of the opener attached to the cover flange. Fig. 3 is a similar view before the opener has been permanently riveted in position. Fig. 4 is a face view of the opener before it is attached to the can. Fig. 5 is a view of the partially formed opener blank. Fig. 6 is a face view of a modified form of opener before attachment; and Fig. 7 is a corresponding view of the partly formed blank.

The opener may be stamped or otherwise formed from heavy tinned iron or other material and pivotally or otherwise permanently secured to the cover or body member of the can so as to properly coöperate with the other member in opening the same. As shown in Figs. 1 to 5 the opener 6 may be pivotally secured to the cover flange 2 by forming an integral pivot portion by punching or stamping out the annular projection 4 into the form indicated in Fig. 3 and securing the same in any desired way as by riveting after it has been inserted in the pivot aperture, preferably adjacent the lower edge of the cover flange. The opener is preferably formed with a suitable projecting finger piece having lateral operating faces and produced by stamping or otherwise and the substantially V-shaped finger piece 8 may be formed as shown in Figs. 1 to 5. This finger piece may be conveniently produced by

forming the blank of the contour shown in Fig. 5 and preferably provided with the raised stiffening rib 7 to prevent undesirable flexure in the plane of the opener. The parts 60 may be stamped up so as to form the upper face 14 and the two lateral operating faces 11, 12, the edges 10 being brought together so that the end fold 13 is lapped over the face 11 to reinforce the same and minimize the exposed edges of the metal. Suitable gripping means may be provided on the opener to co-operate with the other can member, and the integral grip 5 in the form of the fold or hook extending along the upper end of the opener 70 is adapted to grip the can lip 3 and wedge the cover off as indicated in Fig. 1, the lower edge 9 of the flange being raised to the desired extent as the opener is swung laterally as by engagement of the operator's thumb with 75 the finger piece 8. The opener being permanently attached to the cover cannot be lost and is readily returned to normal position as the cover is replaced and also by permanently securing the opener to the cover 80 the can body is left free for use in the ordinary way which is a considerable advantage with cans or boxes containing stove polish compositions.

If desired, the projecting finger piece may 85 be given a substantially tetrahedral form as indicated in Figs. 6 and 7 and this may be readily accomplished by forming the blank of the shape indicated in Fig. 7 after which it is successively folded along the folding lines 90 indicated so as to form the bottom 17 which reinforces the lateral operating faces 15, 16 in connection with the end fold 18 which may be provided, if desired, and turned under the bottom at one side. It is, of course, understood that if desired the parts of these openers may be rigidly held in position by soldering, dipping in tin or otherwise, which also serves to give them a more finished appearance.

Having described this invention in connection with a number of illustrative embodiments thereof, to the details of which disclosure the invention is not of course to be limited what is claimed as new and what is 105 desired to be secured by Letters Patent is set forth in the appended claims.

1. In can openers, a sheet metal opener formed with a projecting finger piece of substantially V-shape having two inclined lateral operating faces, a reinforcing end fold 110 joined to one of said faces and folded over

the other, and a strengthening central rib joining said finger piece, a folded grip along the upper edge of said opener and an integral sheet metal hollow pivot and a can cover provided with a pivot aperture adjacent its lower edge in which said pivot is permanently riveted in such position that said grip is adapted to engage the can lip.

2. In can openers, a sheet metal opener formed with an integral projecting finger piece of substantially V-shape having two inclined lateral operating faces, a reinforcing end fold joined to one of said faces and folded over the other, a grip adjacent the upper end of said opener and an integral hollow pivot formed in said opener, and a can cover provided with a pivot aperture in which said pivot is permanently secured in such position that said grip is adapted to engage the can lip.

3. In can openers, a sheet metal opener formed with an integral projecting finger piece provided with inclined lateral operating faces, gripping means on said opener and an integral hollow pivot formed in said opener, and a can cover provided with a pivot aperture in the portion adapted to be overlapped by the can body and in which said pivot is secured.

4. In can openers, a sheet metal opener formed with an integral projecting finger piece and gripping means and with an integral hollow pivot, and a can member pro-

vided with a pivot aperture in the portion adapted to be overlapped by the coöperating can member and in which said pivot is secured. 35

5. In can openers, a sheet metal opener formed with an integral projecting finger piece having lateral operating faces and an integral hollow pivot, a can member in which said pivot is secured and means on said opener to engage a coöperating can member. 40

6. In can openers, a sheet metal opener formed with a projecting finger piece of substantially V-shape having two inclined lateral operating faces and a reinforcing end fold joined to one of said faces and folded over the other and an integral hollow pivot stamped up from said opener to secure the same in a can member. 45

7. In can openers, a sheet metal opener formed with an integral projecting finger piece and gripping means to engage a can body and with an integral hollow pivot and a can cover provided with a pivot aperture 55 in which said pivot is secured to support the pivot portion of said opener between the overlapping parts of the can when in closed position.
